ILLUMINATED NUMBER OR NAME PLATE

Martin Davidson, Ojai, Calif.

Application August 19, 1937, Serial No. 159,900

4 Claims. (Cl. 40—130)

My invention relates to an illuminated number or name plate of a type in which the light is reflected and either passes through a stencil having the numbers or letters thereon or is obstructed by opaque letters and numbers. In this type of construction using reflected light, a certain amount of difficulty is experienced in maintaining the mirror or mirrors clean and keeping also in a construction by which the mirrors are not subject to weathering conditions. Usually this type of reflecting number or name plate is used out of doors for instance for house numbers or for street signs and located in places in which there is a fixed source of illumination, the light from such source being reflected by the mirror or mirrors. In this type of device the main reflecting mirror is usually placed at about 45 degrees to the stencil or the opaque letters and numbers and the light usually shines downwardly onto the mirror and hence is reflected to either show the illuminated letters and numbers or an illuminated ground with the letters and numbers exhibited as opaque.

An object and feature of my invention in this type of plate is the provision of a molded glass holder open only at the side in which the stencil is to be inserted, thus the device may be molded for instance with a flat or horizontal top, inclined bottom wall at about 45 degrees to the top wall having triangular shaped ends and provided with an open front. This may readily be molded of one piece of glass therefore formed integral. In my invention I either place or locate a mirror on the inclined side, therefore such mirror is protected from the weather when the device is completed. The open side is then closed and sealed preferably by a ground or similar glass plate to which the stencils where a stencil is used, may be secured on the outside of such plate or the opaque numbers or letters may be positioned in front of the frosted plate. Therefore by this construction light may enter through the transparent top and the two triangular ends, such light is then reflected by the mirror outwardly through the frosted glass and exhibits the numbers or letters whether these are stencils or opaques. In another and simpler form of my invention I may have the inclined side mirrored, this being on the outside and then the mirror covered with a protecting coating.

Another detail feature of my invention relates to the manner of attaching the frosted plate and the stencils or letters and numbers and also to the manner of supporting the device, such being preferably by using lugs molded on the triangular

ends and with an iron or similar bracket engaging such lugs. By such construction the assembly may be positioned on an outside wall in a position to be illuminated by house lights or the equivalent.

My invention also includes a construction in which the front face may be molded in the same operation as constructing the rest of the hollow prism. This face may then be sand blasted to give a ground glass surface and the letters or numerals may be painted on such surface or separate letters or numerals glued on this front surface.

My invention also includes making the hollow prism by molding with an open front and then inserting a ground glass to form a closure for this front with the numbers and letters either pasted or painted on the ground glass.

My invention is illustrated in connection with the accompanying drawing, in which:

Fig. 1 is a perspective view of my invention shown attached to a wall.

Fig. 2 is a vertical section on the line 2—2 of Fig. 1 in the direction of the arrows.

Fig. 3 is an enlarged elevation of part of one end to illustrate the molded lug.

Fig. 4 is a partial section similar to Fig. 2 of a modification in which the mirror is on the outside.

Fig. 5 is a perspective view of a suitable holder bracket.

In my invention I form in effect a hollow prism 11 which is defined by a transparent glass wall 12, an inclined transparent glass wall 13 and below this a short rim wall 14 parallel to the top 35 wall and two opposite ends 15, these being triangular in shape. The corner 16 is thus formed integral with the molded hollow block. This construction therefore provides an open front 20 which is illustrated as having a marginal rim 21 40 with a seating shoulder 22. Thus there are a series of surfaces 23 parallel to the top 12, the section 14 at the bottom and the two sides 15.

The front closure designated 25 consists of a glass plate 26 which is preferably of frosted or 45 ground glass or the like but may be transparent if desired or in color. This is held in a channel shaped metal frame 27 secured in place by cement 28 or the like, this binding on the portion 23 and against the shoulder 22. The metal frame 50 has a series of readily bendable tabs 29. Prior to assembling the closure in the construction of Fig. 2 a flat mirror 35 is positioned in the molded block and in contact with the inclined wall 13. The mirrored surface 36 is at the back of this 55

mirror plate and hence is protected from exposure. The glass mirror is held in place by cement or the like 37 at its marginal edges, such edges being adjacent the corner 16, the corner 5 between the inclined side 13 and the ends 15 and that adjacent the bottom section 14.

It will be understood that any types of letters or numerals may be secured on the outside of the frosted plate 26 and as shown in the illustration, these are stencil sheets such as 40 of opaque material and having cut-out or stencil openings such as 41 defining the letter or numeral. The upper or lower tabs 29 may be bent outwardly for insertion of the stencil and 10 then held in place by bending the tabs downwardly over the stencil. Of course it is obvious that opaque numbers or letters may be used. These could be made on a transparent thin glass plate or the like, the letters or numbers being 15 painted or printed on such plate. However if desired the tabs 29 may be positioned and used to hold opaque letters and numbers in position in front of the front plate 26.

In order to readily support the hollow prism I 25 employ a molded lug 50 on each end formed integral with the end 15. Each lug has a rectangular base 51 and a projecting central boss 52. The front edge 53 of the base and the boss is in the same plane as the edge of the rim 21. By 30 this construction there is a side face of the base 51 parallel to and spaced from the face of the end 15 and the side face of the projecting boss 52 is still further spaced from the end 15. A convenient manner of holding the block is by 35 a bracket 60. This is shown formed of wire having two rectangular ends 61 to fit around the boss 52 and to bear against the surface of the base portion 51 of the lug 50. A straight arm section 62 leads parallel to each end wall 15. 40 There is then a straight horizontal portion 63 and two downwardly extending central portions 64. The two portions 64 are connected at an angle 65.

The bracket 60 is intended to be bent at the 45 various angles so that the portions 63, 64, having the angle 65 are in contact with the wall and the bracket is thus attached to the wall by staples 66 or the like. The bracket is thus firmly held in position with the arms 62 extending outwardly 50 therefrom. It is preferable to locate the assembly so that the top wall 12 is slightly inclined to the horizontal. This gives a slight inclination from the vertical of the front closure plate 26. However as the device is usually mounted adjacent 55 an exterior light on a building or where it receives the light from a window, it will be apparent that this slight inclination is an advantage. Light therefore enters through the clearly transparent top 12 and the transparent ends 15. A certain 60 amount of this light shines directly through the front plate 26, however most of such light is reflected by the mirror 35 to pass through the closure glass 26 and thus clearly exhibit the letters and numbers whether these are made in the 65 manner of cut-out stencils or opaque letters and numbers.

In the construction of Fig. 4 the molded prism is made substantially in the same manner as described above, however in the assembly the glass mirror 35 is omitted and the outer surface of the inclined wall 13 is silvered or has a mirrored 5 surface indicated at 70. This mirrored surface is thus on the outside of the transparent wall 13 and may have a protective coating outside of the silvering or other metal used in forming the mirror. It will thus be seen that so far as the 10 reflecting qualities are concerned, there is but little difference as to whether a glass mirror such as 35 is used inside of the hollow prism or the outside of the inclined wall 13 is mirrored on its 15 outside surface but of course where the mirror is placed inside it is not subject to weathering conditions as the hollow prism is entirely closed after attaching the front closure plate 26.

It will be obvious that it is not necessary to use a metal frame for holding the frosted glass 20 26 in place in the front opening. This may be cemented directly against shoulders in the molded glass. Moreover the letters and numerals may be pasted on the frosted glass or painted 25 thereon.

Various changes may be made in the details of the construction without departing from the spirit or scope of the invention as defined by the appended claims.

I claim:

1. In a device as described, a hollow molded glass prism having a transparent top wall forming a plane surface, an inclined bottom wall at substantially 45 degrees thereto, a lower rim wall connected to the inclined bottom wall, transparent end walls substantially triangular in section, the said walls having a marginal rim forming a plane surface with a seating shoulder positioned inwardly from the rim, a closure glass fitted against said shoulders, letters or numerals secured on the outside of the closure glass and a mirror attached to and parallel to the inclined bottom. 35
2. In a device as described and claimed in claim 1, the mirror being formed with a separate sheet of glass located inside the hollow prism and in contact with the inclined bottom. 45
3. In a device as described and claimed in claim 1, the mirror being formed with a mirrored surface on the outside of the inclined bottom. 50
4. In a device as described a hollow molded glass prism having a transparent top wall forming a plane surface, an inclined bottom wall at substantially 45 degrees thereto, transparent end walls substantially triangular in section, the said walls having means forming a marginal rim with a plane surface forming the edge, the rim having a seating shoulder thus leaving a large opening, a closure glass fitted in said opening against the shoulders, letters or numerals secured on the outside of the closure glass and a mirror attached to and parallel to the inclined bottom. 55
